UNITED STATES PATENT OFFICE.

HENRY CORMACK, OF QUINCY, MASSACHUSETTS.

RADIO TUNING DEVICE.

Application filed August 27, 1923. Serial No. 659,540.

To all whom it may concern:

Be it known that I, HENRY CORMACK, a citizen of the United States, residing in Quincy, in the county of Norfolk and State 5 of Massachusetts, have invented an Improvement in Radio Tuning Devices, of which the following description, in connection with the accompanying drawings, is a specification, like characters on the drawings representing like parts.

This invention relates to a tuning coil for radio receiving apparatus.

The object of the invention is to provide a tuning coil for radio receiving apparatus 15 of novel and improved construction by which extremely exact and sensitive tuning may be obtained, and which in addition is of a simple and durable construction.

To this end, the tuning coil comprises a 20 wire bent to form a coil and preferably a plurality of coils, and having provision for connection to one point in the circuit to be tuned, and a contact member capable of connection to a second point in the circuit, and 25 arranged to bear upon the wire of the coil or coils and to move lengthwise thereof around the coil or coils, the contact member and the coils being arranged to be capable of relative rotary movement to permit the contact member to bear upon successive portions 30 of each coil. In the preferred form of the invention the wire is helically wound about an insulating tube rotatably mounted in suitable supporting members at its opposite 35 ends and the contact member is mounted upon a pivoted arm arranged to permit the contact to move transversely across the successive coils of the wire as the tube is rotated, and to continuously bear against the wire of 40 successive coils.

These and other features of the invention will be hereinafter described and particularly pointed out in the claims at the end of this specification.

45 In the drawings illustrating the preferred embodiment of the invention, Fig. 1 is a side elevation of the improved tuning coil;

Fig. 2 is a front elevation of the same;

50 Fig. 3 is a vertical section through the axis of the drum shown in Fig. 1; and

Fig. 4 is an enlarged detail illustrating the construction of the pivoted contact arm.

Referring to the drawings, the improved tuning coil comprises a turn or coil of wire 55 10, and preferably a plurality of coils arranged to be capable of connection at one

point 12 in the circuit to be tuned, and a contact member 14 arranged to bear upon the wire of the coil or coils and itself capable of connection to a second point 15 in the circuit to be tuned. The coil or coils of wire 10 and the contact member 14 are arranged to be capable of relative rotary movement so as to permit the contact member to be moved lengthwise of the wire comprising each turn or coil 10 upon the relative rotary movement of the coils and contact member, and in this manner to permit contact to be made at all points in each coil, thus securing an exact and sensitive tuning of the circuit.

As herein shown, a bare wire is wound in the form of a helix upon an insulating tube or cylinder 20 provided with end members 21 of insulating material. The helix may be provided with any desired number of coils 70 10. Each end member 21 is provided with a bolt 22 projecting outwardly through a hole therein, and a lock nut 23 for securing the bolt 22 in fixed relation to the end members 21. The ends of the bolts 22 are preferably tapered and journaled in cone shaped bushings 25 fitted in and secured to metal supporting brackets 26 affixed to a supporting piece 27 of insulating material forming a supporting base upon which the tuning coil 75 is mounted. One end 28 and preferably both ends 28 29 of the wire comprising the coils 10 are soldered to the bolts 22, as illustrated in Fig. 3, to provide a fixed electrical connection between the coils and the metal supporting brackets 26. One of the metal supporting brackets 26 is connected with a binding post 30 by a wire 31 extended beneath a portion of the insulating supporting piece or base 27 as illustrated in Fig. 1. The movable contact member 14 may and preferably will comprise a metal point or finger 33 provided with a groove 35 in the end thereof to permit the said point or finger to fit over the wire of each coil 10, and in winding the coils upon the insulating cylinder or tube 20 sufficient space is left between adjacent coils to permit the metal point or finger 33 to engage each coil straddling the wire without coming in contact with the wire of adjacent coils. The metal point or finger 33 comprising the contact member may and preferably will be mounted upon the end of the arm 14 pivotally mounted upon the supporting piece or base 27 to be capable of a movement toward and from the supporting drum or cylinder 20 and also longitudinally 80 85 90 95 100 105 110

thereof. As herein shown, the pivoted arm 14 is curved upwardly over the drum or cylinder 20 to cause the metal point or finger 33 to bear at substantially the top of the 6 coils. The contact arm 14 is herein shown as pivoted at 45 in the forked end of a collar 46 which bears upon a washer 47 resting upon the top of an insulating block 48 and held in position upon the block by a screw 10 50 extended downwardly into the block.

The screw 50 may and preferably will engage a wire 57 inserted into a hole 58 in the block 48, to bind the same firmly between it and the walls of the hole and electrically connect the contact finger 33 with the wire 57, which is extended under the supporting piece or base 27 and connected to a binding post 59, at which connection may 15 be made to the second point in the circuit 20 to be tuned. The upper end of the block 48 is preferably provided with a recess 51 in which a coil spring 52 is received, and which latter, when the screw 50 is screwed down into the block, is placed under compression 25 sufficient to cause the washer 47 to frictionally engage the under surface of the collar 46 with a relatively light pressure to exert a retarding effect upon the lateral movement of the pivoted arm while at the same 30 time permitting the arm 14 to be moved laterally as the grooved end of the contact point or finger 33 follows around the successive coils 10 of the helix. In addition, the coil spring 52 serves to yieldingly hold 35 the collar 46 in engagement with the head of the screw 50, thus establishing a positive electrical connection at all times and under all conditions at this point. The pivotal connection of the arm 14 at 45 permits the 40 said arm to be moved toward and away from the helix for the purpose of enabling the metal point or finger 33 to be disengaged from any particular coil of the helix and quickly moved axially of the helix to 45 engage a different coil. The arm 14 may be provided with an insulating knob 60 for enabling the operator to lift the pivoted arm for this purpose. In addition, the knob 60 serves as a weight to hold the metal contact point or finger 33 in light but firm 50 engagement with the helix.

The cylinder or drum 20 may be rotated by hand, and for this purpose an insulating knob 62 is secured upon the extended end of 55 one of the bolts or shafts 22 of the drum 20, and as the latter is rotated, the entire length of a coil of the helix is engaged with the contact member or finger 33 for each revolution of the drum; and as the latter is rotated, every portion of the coil against which the contact member or finger 33 bears is engaged with the latter, with the result 60 that very sharp tuning is effected. The helical form of the coil causes the contact finger 33 to be moved axially with relation to

the drum so as to bring the contact finger into engagement with successive coils of the helix.

In this manner the entire wire of each coil may be utilized to obtain an exact and sensitive tuning of the circuit and thus a large range of adjustment is afforded between each winding or coil, whereas in tuning coils as heretofore constructed and known to me, each coil was either tapped at a single point in its periphery by a metal slider rubbing across the wires axially of the coils, or by a plurality of wire taps, one for each group of coils. In the first instance the range of adjustment is from one coil to the 70 next, and in the second instance from one group of coils to the next group, intermediate the taps not utilized nor available for making a sensitive or extremely accurate tuning. The advantages of the present construction of tuning coil over these prior constructions of tuning coils will therefore be 80 apparent. The helical form of wire coil enables the contact member or finger to be moved axially of the drum in opposite directions. 85

One embodiment of the invention is herein shown and described, but it is not desired to limit the invention to the particular construction shown. 90

Having thus described the invention, what is claimed is:

1. A tuning coil for radio receiving apparatus, comprising a supporting base, a drum rotatably mounted thereon, a helix of conducting material upon the drum, and a contact member co-operating with the helix comprising an arm mounted upon the supporting base to have pivotal movement axially of the helix and toward and away 100 from the helix. 105

2. A tuning coil for radio receiving apparatus, comprising a supporting base, a drum rotatably mounted thereon, a helix of conducting material upon the drum, a contact member co-operating with the helix comprising an arm mounted upon the supporting base to have pivotal movement both axially of the helix and toward and away from the helix, and means for frictionally 110 restraining the axial pivotal movement of said contact member. 115

3. A tuning coil for radio receiving apparatus, comprising a supporting base, a drum rotatably mounted thereon, a helix of 120 conducting material upon the drum and a contact arm co-operating with said helix, a collar rotatably mounted on said base and to which the contact arm is pivoted to move toward and away from said drum, and a 125 spring co-operating with said collar.

4. A tuning coil for radio receiving apparatus comprising a rotatable helix of conducting material, and means for mounting 130 a contact member co-operating therewith,

said contact member being capable of movement axially of the helix by rotation of the latter and of movement toward and away from said helix to be engaged with and disengaged therefrom and to be manually moved axially of the helix.

5. A tuning coil for radio receiving apparatus, comprising a supporting base, a drum rotatably mounted thereon, a helix of 15
10 conducting material upon the drum, and a

contact member cooperating with the helix comprising an arm mounted upon the supporting base to have pivotal movement both axially of the helix and toward and away from the helix, and a grooved metal finger carried by the arm and straddling one of the convolutions of the helix.

In testimony whereof, I have signed my name to this specification.

HENRY CORMACK.
